BOTTLE CRATE

Fred G. Krueger, Norwood, and Fred H.
Hudepohl, St. Bernard, Ohio

Application June 14, 1935, Serial No. 26,630

6 Claims. (Cl. 217—20)

Our invention relates to crates and more especially to crates used for containing milk bottles in the dairy business. Such crates are subjected to rough handling while sustaining the weight of the bottles when the latter are filled and are being delivered to the customer as well as when the crates containing the empty bottles are being returned to the dairy. The crates also are subjected to extremes of heat and cold and steaming for purposes of cleaning and sterilizing. The preferred combination of materials is wood and metal; and the wood is especially adversely affected under the above conditions. It is therefore necessary to provide in any such crate a substantial and strong attachment of the metal parts to the wood parts.

A very common example of such crates is that in which four upright wooden walls are connected at their corners and suitably re-enforced by metallic elements; the interior of the crate being crossed in both directions by a series of metal wires or rods having their opposite ends fixed in opposite wooden walls of the crate. A series of these wires or rods is arranged horizontally across the bottom portion of the interior of the crate, to be contacted by the bottoms of the bottles; these wires or rods extending in only one direction; while additional series of wires or rods above this single series are arranged to extend at right angles to each other to form compartments each of which receives one of the bottles.

It is with a crate of this character that our invention is especially concerned. These crates have become fairly well standardized as to proportion and size; being of oblong shape with the lower supporting wires running lengthwise. As is well known in this kind of crate it is necessary to support these supporting wires intermediate of the end walls of the crate in which the ends of the wires are fixed so that these wires will form a sufficiently rigid support for the bottles and not be bent out of shape under the stresses of handling the crate and of inserting the bottles into the compartments. It also has been found to be of advantage to provide a connection or connections between the intermediate re-enforcement of the lower wires and one or more of the upper series of compartment-forming wires; so that these upper wires will be sustained in shape against the stresses of downward striking of the bottles when the bottles are inserted; as well as against upward bending. This upward bending is most liable to occur when the handlers of the crates grasp the compartment-forming wires for

lifting the crates when the crates are empty or partly empty.

It is an object of our invention to provide the intermediate re-enforcement of the bottle supporting wires or rods in such a manner that it will be very rigid and effective in its re-enforcing function and yet will be very readily assembled with the other parts of the crate.

A further object is to provide such re-enforcing means in such a manner that it will effectively connect the compartment-forming wires and the bottle supporting wires so that each set of wires efficiently acts as a re-enforcement to each other set of wires; and at the same time to have the entire assembly such as may easily be put together in the manufacture of the crate.

We attain the above objects as well as other objects which will appear in the course of the following description by the structure illustrated, for example, in the accompanying drawing in which:

Fig. 1 is a vertical longitudinal section of the crate on the line 1—1 of Fig. 2;

Fig. 2 is a vertical cross-section of the same on the line 2—2 of Fig. 1;

Fig. 3 is a perspective detail view of the cross beam of the intermediate re-enforcement;

Fig. 4 is a detail perspective view of one of the connecting elements by which the cross beam is tied to the upper set of compartment-forming wires;

Fig. 5 is a partial detail perspective view corresponding to Fig. 3 and illustrating a modification of the cross beam; and

Fig. 6 is a similar view illustrating another modification.

The crate herein illustrated as an example has the wooden end walls each made up of a bottom slat 1 and three upper slats 1a; and wooden side walls each made up of a lower slat 2 and three upper slats 2a. These slats are joined at the meeting corners by suitably formed sheet metal outer angle bars 3 and similar inner angle bars 4 which will be understood to be riveted or otherwise suitably rigidly secured to the slats as is well-known in the art; so that the side and end walls are rigidly joined and are re-enforced at their corners, outside and inside, by these angle bars. Also as is well-known in the art, the inner angle bars 4 have upstanding stacking guides 5. The upper two of the end slats 1a have recesses 6 and 6a to admit the hands for lifting the crate, as is usual.

As here shown, the crate is provided for receiving twelve bottles in three longitudinal rows

of four bottles each. It will be understood, however, that crates for different numbers of bottles and with different arrangements of the bottles are used in the art and that our invention is applicable to any such different number or arrangement. For the arrangement as shown three pairs of bottle supporting wires 7 are provided with their end parts rigidly secured in the lower end wall slats 1 in any suitable manner well known in the art. Each pair of wires 7 is thus arranged to support a row of four bottles; and to define the middle row of compartments from the two outer rows two pairs of longitudinal compartment-forming wires are provided. The lower wires 8 are spaced relatively a short distance upward from the plane of the supporting wires 7; and the upper wires 9 are spaced a considerably greater distance upward from the lower wires 8. To define the four compartments of the longitudinal rows corresponding series of lower cross wires 10 and upper cross wires 11 are provided having their opposite ends rigidly secured to the wall slats 2 and 2a; these cross wires 10 and 11 come very close to or in contact with the longitudinal wires 8 and 9 where they cross these wires. This is a usual construction of milk bottle crates; and it is explained in detail to permit the clear description of our invention in which this construction is involved.

As before stated, it is usual to provide some kind of rigid re-enforcement for the wires 7 as well as the wires 8 and 9 at one or more places intermediate of the length of the supporting wires 7. We have improved this re-enforcing means by the provision of the beam 12 which comprises at least one vertical web 13 with apertures 14 through which pass the respective bottle supporting wires 7 near the lower edge of the web; and means near the upper edge of the web 13 to engage over one of the lower cross wires 10; as well as openings 15 through which pass the lower longitudinal compartment defining wires 8. The upper means for engaging over the cross wire 10 is so provided that this beam 12 may be readily inserted after cross wire 10 has been fully secured in the crate side walls but before the longitudinal wires 7, 8 and 9 have been inserted.

This is of considerable advantage in assembling the crates not only because a large proportion of the wires, that is all of the cross wires 10 and 11, may be fully secured without complications as to the assemblage of the re-enforcing means and the longitudinal wires 7, 8 and 9 therewith. In fact by having the transverse wires already fully secured in position these may be made to support the re-enforcing structure so as to greatly facilitate the assemblage of the longitudinal wires in the crate therewith.

As we illustrate it herein, and as is preferred, the upper means of the beam 12 for engaging over the cross wire 10 consists of a series of tongues integral with the web 13, which tongues are bent over in inverted U shape to hook over the wire 10 as the beam 12 is passed down in the crate. The beam 12 is made of such length as to fit snugly between the opposite lower side wall slats 2. It thus firmly re-enforces these slats 2 against inward bending or breaking and also by its close engagement with the slats at the ends is largely prevented from moving out of its proper position with its web 13 vertical.

As here shown, the beam 12 has tongues 16 bent as above described and extending longitudinally of the beam 12 for a considerable distance

each way from each opening 15 that receives a longitudinal wire 8. So that such tongue or hook 16 may engage amply down along side the cross wire 10 with its free portion, this portion is provided with a notch 17 to receive the longitudinal wire 8; the middle portion of the edge of this notch preferably being in horizontal alignment with the top edge of the respective opening 15 so as to snugly engage the top of the respective longitudinal wire 8. This helps to prevent rocking of the beam laterally on the cross wire 10. Also as the longitudinal wires 8 pass snugly through the openings 15 and against the upper edge of the notch 17 as well as against the lower side of the cross wire 10, the beam 12 is very firmly connected to the intermediate portions of the cross wire 10.

At its end portions the beam 12 has the tongues 16a bent as above described and hooking over the cross wire 10 immediately adjacent to the side walls 2 in which the end portions of the cross wire 10 are fixed. Thus the beam 12 is firmly supported by the crate side walls to resist downward displacement; so that it is adapted to effectively support the longitudinal bottle supporting wires 7 and fit snugly through the openings 14 of the lower portion of the beam. To add rigidity to the beam its web 13 preferably has the horizontal flange 18 along its lower edge throughout its length. This flange is especially desirable because it permits of a minimum of extension of the beam 12 below the supporting wires 7 which the beam supports and yet retains the required amount of metal below the openings 14 to avoid undue weakening of the beam by the provision of these openings. Also the openings 14 are preferably placed down close to the flange 18 so that the longitudinal wires 7 may firmly engage the top of this flange 18 so that this also affords some provision against rocking of the beam laterally.

As before stated, milk bottle crates have become very closely standardized as to size owing to the fact that they must receive bottles of standard size and also must pass through machinery in cleaning, sterilizing and other treatment in the dairy plants so that there is no margin for variation either in external or internal dimensions of the crate. For this reason it is often necessary to construct the metal parts of the crate with a very close margin relative to the size of the bottles. For example, where the tongues 16 hook over the cross wire 10 in our invention there is involved a thickness of the metal at both sides of this wire 10. In some cases even one thickness of metal at this point where the cross wire 10 is tangent to the bottle will prevent the free entrance of the bottle down to the supporting wires 7. The interference of one thickness of metal at this tangent point is avoided by limiting the lengths of the tongues or hook portions 16 and 16a along the beam 12 as above described. However in some cases the thickness of metal at the other side of the wire 10 would prevent free insertion of the bottle. In such cases the beam may be modified as the beam 12a in Fig. 5 where the web 13a has a compound bend 13' throughout its length, so that each portion 13b that extends between tongues or hook portions 16, or 16 and 16a, lies under the adjacent side portion of the transverse wire 10. If the relative size of the bottles and the crate interior is such as to permit a thickness of metal at each side of the wire 10 it would be unnecessary to discontinue the mate-

rial between tongues 16 or tongues 16 and 16a; so that a continuous flange might be bent to hook over the cross wire 10 as illustrated in Fig. 6 where the beam 12b has the continuous hooked flange 16b.

The beam 12, 12a or 12b constructed and assembled as above described will effectively unite the bottle supporting wires 7, the metal cross wire 10 and the lower compartment-defining wires 8 into a single rigid structure which will very effectively resist either upward or downward distortion.

In order to impart the required strength to the upper longitudinal wires 9 and the middle cross wire 11 for the purposes before mentioned, we provide vertical connecting elements 19 between the lower structure above described and the upper wires 9 and 11; which elements are adapted to resist both upward and downward movement of the wires 9 and 11 relative to the rigid lower structure. As here shown, each hook or tongue 16 has a slot 20 in its top aligned with the opening 15 through which the wire 8 passes. Each element 19 is in the form of a flat metal strip which extends down through this slot 20 between the cross wire 10 and the side of the tongue or hook portion 16 that is next to the web 13; the lower end portion of this strip having an opening 21 through which the longitudinal wire 8 passes to fit snugly therein. The upper end portion of the strip is bent to form a hook 22 which engages down over the transverse wire 11; and the strip and the free end portion of the hook 22 have the aligned openings 23 and 24 respectively through which the longitudinal wire 9 passes snugly with the result that this hooked upper portion of the element 19 binds the longitudinal wires 9 and the cross wire 11 together with a connection that also is able to resist either upward or downward stresses on the wires 9 and 11.

As here shown there are two sets of upper compartment-defining wires, the lower one of these sets comprising the longitudinal wires 9a and the cross wires 11a, the latter merely passing alongside the connector 19 while the longitudinal wire passes through the connector. In other crates this upper set is omitted; and it will be understood that the connector 19 would then connect with the wires 9a and 11a as here shown for the upper wires 9 and 11.

In assembling the crate, as before alluded to, the wooden side and end walls may be fully connected and all of the transverse wires may be inserted and secured in the usual manner. Then the beam 12 may be inserted, hooked over the transverse wire 10 and the strips 19 may be inserted down through the slots 20 to hook over the upper transverse wire 11. Then all the longitudinal wires 7, 8 and 9 may be inserted through one end of the crate and through the several openings in the beam and in the connecting elements 19; after which these longitudinal wires may be firmly secured to the ends of the crate in any manner well known in the art.

We have shown certain modifications but it will be understood that other modifications may occur and therefore we are not limited to the precise disclosure herein, but what we claim as new and desire to secure by Letters Patent is:

1. In a bottle crate comprising upright walls, a plurality of sets of bottle supporting wires and a compartment-defining wire above and intermediate of the sets of supporting wires, the several wires being secured to the respective crate walls,

and a compartment-defining wire crossing above the above-mentioned compartment-defining wire and secured to respective crate walls, a beam through which the supporting wires and the first-mentioned compartment-defining wire extend, said beam having a part hooked over the last-described compartment-defining wire adjacent to the compartment-defining wire that passes through the beam, said beam extending close to the respective crate walls and having additional portions hooked over said wire adjacent to said walls, the hooked-over portions being spaced to permit entrance of bottles closely along side the wire over which they hook.

2. A bottle crate as set forth in claim 1 in which the beam has a portion intermediate of its hooked-over portions displaced under the wire so that bottles may be inserted close to both sides of the wire.

3. In a bottle crate as a re-enforcement for the lower bottle supporting wires and crossing compartment-defining wires above the supporting wires, a beam having the supporting wires extending therethrough and having means to hook over one of the compartment-defining wires as the beam is passed downwardly in the crate assembly, said beam having another one of said compartment-defining wires passing through it and securing it in its hooked-over relation to the first-mentioned compartment-defining wire, said beam comprising an upright web portion through which the wires extend, and a bottom laterally extended flange portion with the supporting wires in engagement with the top of said flange.

4. In a bottle crate as a re-enforcement for the lower bottle supporting wires and crossing compartment-defining wires above the supporting wires, a beam having the supporting wires extending therethrough and having means to hook over one of the compartment-defining wires as the beam is passed downwardly in the crate assembly, said beam having another one of said compartment-defining wires passing through it and securing it in its hooked-over relation to the first-mentioned compartment-defining wire, said beam comprising an upright web portion through which the wires extend, which has its upper portion bent to form the hooking-over means which is of inverted U-shape with sides to engage the opposite sides of the wire and having a free edge with a notch in which is engaged the compartment-defining wire that secures the means in hooked-over relation.

5. In a bottle crate comprising four upright walls, bottle-supporting wires extending between opposite walls and secured to said walls, and upper and lower sets of compartment-forming wires crossing each other above said supporting wires and secured to the respective opposite walls, a re-enforcing means having said supporting wires extending through it and having an extension extending over a lower one of the compartment-forming wires with compartment-forming wires extending through said member below the just-mentioned compartment-forming wire and locking said wire to said extension, said extension having an opening spaced across said wire from an upright portion of the re-enforcing member, and a connecting element engaging upper ones of the compartment-forming wires and extending down through said opening and holding said lower compartment-forming wire between itself and said upright portion, said connecting element extending below said wire and

having extending through it the compartment-forming wire that extends through the re-enforcing member.

6. A bottle crate as set forth in claim 1 in which the part of the beam through which the wires extend is an upright web, said beam also

comprising a bottom laterally extended flange portion continuous along those parts of the length of the beam between the spaced hooked-over portions.
